INVENTOR

Erwin, Coheeler & Cholard
BY
ATTORNEY

UNITED STATES PATENT OFFICE.

GEORGE C. ROEDL, OF WEST ALLIS, WISCONSIN.

WINDOW-SASH COUNTERBALANCE.

Application filed February 21, 1927. Serial No. 169,689.

My invention relates to improvements in window sash counter-balance.

The object of my invention is to provide a spring counter-balance for window sashes which will not only be substantially constant in its effective support of the sash to be balanced, but which will be easily installed in any standard window frame. Another object of my invention is to provide a sash counter-balance for a plurality of window sashes mounted in a single frame and comprising a plurality of springs interconnected by a single cord or chain for simultaneous counter-balancing of said sash. It is a further object of my invention to provide an easily adjustable spring balance.

In the drawings:

Figure 1 is a front vertical elevation of two sashes mounted in a window frame and showing a portion of the sash and frame cut away to exhibit my device.

Figure 2 is a sectional view of a side elevation of a window frame equipped with my improved counter-balance.

Like parts are identified by the same reference characters throughout the several views.

My invention may be incorporated into any standard window frame such as the one shown at 1 in the drawings. As is customary in the construction of such frames, provision is made for guideways for upper and lower sashes 2 and 3 respectively, so that the said sash may be slidably moved upwardly or downwardly as desired.

Standard construction of window frames also provides a compartment adjacent the vertical member 4 of the frame and usually walled in upon the outside of the compartment by studding of other portions of the frame of the building as shown at 5. It is within this compartment 6 that my device is installed. Pulleys 7 and 8 may be provided as shown in Fig. 1 at such points in the frame member 4 as to be concealed by the sashes 2 and 3 at all times, or they may be positioned at the upper ends of the guideways as is customary in most window construction and as shown particularly in Fig. 2.

My improved counter-balancing device particularly comprises a continuous spring tensioned cord or chain 10 extending from a pocket 11 in the lower rail 12 of the lower sash 3, through a diagonal bore 13 and the cord groove 14 over pulley 8 into the com-

partment 6, where it follows continuously through a series of pulleys 14', 15 and 16 and over the large pulley 7 to the pocket 17 at the end of groove 18 in the side of the side member of sash 2. This cord or chain 10 is constantly under tension imposed thereon by means of springs 14^a, 15^a and 16^a which are disposed in the compartment 6 as follows. A pair of hooks 20 secured to the sill 21 provide anchorage for springs 14^a and 16^a which are held in an erect position by the cord upon which they are adapted to pull. The hook 22 secured at the top of the frame within the compartment 6, provides anchorage for spring 15^a which in turn resiliently supports a pulley 15 over which the cord or chain 10 is entrained.

It will be obvious from the above description that the system of springs and pulleys over which the cord 10 is entrained, will provide an extremely resilient counter-balance for the window sashes 2 and 3, for the springs 14^a, 15^a and 16^a may be made long and flexible in the ample space provided in the compartment 6 to the end that any movement of the sashes 2 and 3 within their guideways may be possible without variation substantially in the amount of counter-balancing action induced by said springs. Installation upon the anchoring hooks 20 and 22 compared with the usual installation of counter-balancing weights will be simple and easy and a provision for an adjustment hereinafter described will enable any workman to quickly install my device in any standard window frame.

Provision of a pocket 11 at the bottom of sash 3, and the diagonal bore 13 extending from said pocket to the other groove 14 provided for cord 10, forms a means for quick adjustment at any time of my spring balance. Upon the initial installation of my device in a window frame, the cord will be extended over the pulleys as indicated above and will be extended through the guideway 14 and through the bore 13, so that the extended end of the cord or chain will be subject to easy manipulation through the pocket 11. Little practice will be necessary to enable any workman to judge the amount of tension necessary for a particular window installation. A readjustment may be easily and quickly made by simply pulling the cord from the pocket 11 and tying the knot or providing any other stop for the

cord or chain at greater or lesser lengths for adjustment of the spring tension.

In installations where there is likelihood that moisture might accumulate in pocket 5 11 and deteriorate the cord at the point where the knot is secured in said pocket, a small amount of putty inserted in the hole after the adjustment has been made will protect the cord against such deterioration.

10 I claim:

1. The combination with a frame providing guideways, of a plurality of sash reciprocable in said guideways, a single cord interconnected between said sash, and a plurality of counter-balancing springs providing tension upon said cord.

2. The combination with a frame provid-

ing guideways, of a plurality of sash reciprocable in said guideways, a single cord interconnected between said sash, and a plurality of springs providing counter-balancing tension upon said cord in all positions of said sash in said guideways. 20

3. The combination with a frame providing guideways, of a plurality of sash reciprocable in said guideways, a plurality of springs attached at spaced points to the frame, a pulley for each of the springs and a single cord unconnected between the sash and passing alternately over the pulleys, whereby to counter-balance the sash under the control of said springs. 25

GEORGE C. ROEDL.
